UNITED STATES PATENT OFFICE.

FRANK HINTON, OF DECATUR, ILLINOIS.

MEANS TO PREVENT FLOODING BASEMENTS, &c.

1,329,405.

Specification of Letters Patent.

Patented Feb. 3, 1920.

Application filed August 16, 1919. Serial No. 318,028.

To all whom it may concern:

Be it known that I, FRANK HINTON, a citizen of the United States, residing at Decatur, in the county of Macon and State of Illinois, have invented certain new and useful Improvements in Means to Prevent Flooding Basements, &c.; and I do hereby declare the following to be a full, clear, and exact description of the invention, such as will enable others skilled in the art to which it appertains to make and use the same.

This invention relates to devices used to prevent water and sewer gas from escaping from a drain pipe or the like and entering a room or building occupied as a dwelling or for other purposes, and has for its object mainly to provide simple and efficient means to prevent the flooding of basements in cities, towns and villages during a flood or heavy and unusual downpour of rain, causing the sewers to overflow. Other objects are to prevent the escape of sewer gas and foul odors that may enter a basement or other part of a dwelling through a drain pipe or the like.

The invention will first be hereinafter more particularly described, with reference to the accompanying drawings, which form a part of this specification, and then pointed out in the claims at the end of the description.

In said drawings—

Figure 1 is a plan view of a device embodying my invention;

Fig. 2 is a vertical sectional elevation of the same, and

Fig. 3 a detail sectional view showing the connection between the perforated plate overlying the cap-plate of a drain pipe and the superposed imperforate presser plate.

Referring to said drawings, in which the same reference letters are used to denote corresponding parts in different views, the letter A denotes a cap-plate secured on the end of a drain pipe P, which connects with a sewer for conducting rain water and drainage from the basement or other part of a dwelling house; the combination, in this instance being made by screwing the end of the pipe in a threaded hole in the cap-plate, as shown in Fig. 2. On the cap-plate A is secured a perforated plate B, through the perforations of which water may flow into the drain pipe; the two plates being separated sufficiently to provide a water space between said plates around and over the open end of the drain pipe. This space may be provided

by forming on or attaching to the perforated plate marginal enlargements or strips b, b, which extend entirely around or on all side edges of the plate to prevent forming a gap through which water or gas may escape, and to seal the joint a correspondingly shaped gasket C, of rubber or other suitable material is placed between the marginal portions or edges of the two plates, as shown. The two plates may be firmly secured together by fastening bolts D having reduced threaded ends d which are screwed into interiorly threaded holes in the plates, as shown in Fig. 3, or by other means. The bolts D also have reduced upper end portions which are passed through holes in the top-plate E which rests upon the shoulders at the upper ends of the enlarged or main body portions of the fastening bolts and is secured thereon by nuts d¹. However, instead of bolts having reduced end portions, bolts of uniform size from end to end may pass through sleeves which will serve the same purpose as the enlarged intermediate portions of the fastening bolts, and other means may be employed for securing the perforated plate and cap-plate together and mounting the cover plate E¹ and the top plate E thereon with provision for upward and downward movement of the cover plate, which in this instance, is permitted by passing the enlarged or body portions of the fastening bolts freely through openings or holes of proper size in the cover plate, as shown in Fig. 3. The cover-plate E¹ has swiveled thereto, centrally thereof, an adjusting device for raising and lowering it to uncover or cover and close the perforations in the plate B, which takes the place of the usual perforated plate over the end of the drain pipe as heretofore ordinarily employed for carrying off drainage from basements and cellars or basement toilet rooms. As shown, the adjusting device consists of a rotatable screw G, carried by the top plate E, and having secured on its upper end a hand wheel or other suitable handle H, for turning it, said screw having reduced end portions and said hand wheel having a central hole to receive the reduced upper end g of the screw on which is placed a nut for securing the hand wheel or other device thereon, said reduced end g being square or angular in cross section to cause the hand wheel and screw to rotate together. The screw also has a reduced lower end g¹, which is rotatably fitted in a hole through

- the swivel-plate I and is retained therein by a washer K which is secured on said reduced end underneath the swivel plate by a pin or key or other suitable device, such as 5 is ordinarily employed for similar purposes, so that the screw may be rotated to raise and lower the cover-plate E¹ and thereby uncover or close the perforations in the drain-pipe plate B.
- 10 A gasket L of rubber or other suitable material is made fast to the underside of the presser-plate so as to fit closely upon and effectually seal the holes in the perforated plate and prevent the escape of water or 15 sewer gas when the presser plate is screwed down tightly upon the perforated plate.
- I thus provide a very simple, efficient and inexpensive device or attachment to drain-pipes that will prevent back-flow of water 20 and the flooding of basements and toilet rooms on the lower floors of dwellings or stores where drain pipes are used, and will also effectually prevent sewer gas from escaping through the drain pipe and entering 25 a dwelling house or other building.
- It will be understood of course that various changes may be made in the details and arrangement of parts without departing from the spirit and scope of my invention.
- 30 Having thus described my invention, what I claim as new and desire to secure by Letters Patent is:—
1. A device of the character herein described comprising a cap-plate having an opening therein to receive the end of a drain pipe, a perforated plate placed over said cap-plate and spaced therefrom so as to provide a water-space around the open end of said pipe, a fixed top-plate located above 35 said perforated plate, a vertically movable cover-plate for said perforated plate arranged between it and said top-plate, and means for raising and lowering said cover-plate to open or close the openings in said 40 perforated plate; said cover-plate having on the under side thereof a gasket of rubber or other suitable material adapted to seal the openings in said perforated plate and prevent the escape of water or sewer gas when 45 the cover-plate is held down tightly on said perforated plate.
  2. In combination with a drain pipe, a cap-plate having an opening therein to receive the end of said pipe, a perforated plate placed over said cap-plate and spaced therefrom so as to provide a water space around and over the open end of said pipe, bolts 50 rising from said perforated plate having
- their lower ends screwed therein, a top-plate mounted on said bolts, a cover-plate slidably supported on said bolts between said top-plate and said perforated plate, and means for raising and lowering said cover-plate to open or close the openings in said perforated plate; said means comprising a rod screwed into a threaded opening through said top-plate and having its lower end swiveled to said cover-plate and provided on its upper end with a suitable handle.
3. A device to prevent back flow and escape of water and sewer gas from drain pipes, comprising a base-plate having a threaded opening therein for attachment to a drain pipe, a superposed drain outlet plate spaced from said base-plate to form a water space over and around the open end of the drain pipe and having a series of perforations therein, said plates being secured together by means of bolts screwed therein and rising therefrom, a vertically movable cover-plate normally resting upon and closing the openings in said perforated plate, and means for raising and lowering said cover-plate to open and close said perforations, said means consisting of a fixed member supported on said bolts above said cover plate and having a central threaded opening therein and a rod screwed in said opening and having its lower end swiveled to said cover plate and provided on its free end with an operating handle.
4. An attachment for drain pipes to prevent back flow and escape of water and sewer gas, comprising a perforated plate arranged over the open end of the pipe, a vertically adjustable plate adapted to cover and close the openings in said perforated plate, a gasket of rubber or other suitable material having an open center being secured on the under side of said perforated plate to water-seal the joint and provide an uninterrupted space around the open end of the drain pipe, a gasket of rubber or other material made fast to the underside of said adjustable plate and adapted to water-seal the openings in said perforated plate, and means for raising and lowering said adjustable plate to open and close the openings in said perforated plate.
- In testimony whereof I affix my signature in the presence of two witnesses.
- FRANK HINTON.
